CIRCUIT FOR MULTI-APERTURE MAGNETIC CORE DEVICES
David Nitzan, Palo Alto, Calif., assignor to AMP Incorporated, Harrisburg, Pa.
Filed Aug. 30, 1963, Ser. No. 305,779
9 Claims. (Cl. 340—174)

This invention relates to an improved circuit and method for multi-aperture magnetic core devices of the type utilized to manipulate intelligence in binary form.

One of the more successful techniques developed relative to the use of multi-aperture cores for handling intelligence, is that generally shown and described in the article, "MAD-Resistance Type Magnetic Shift Registers," by Dr. David R. Bennion, 1960 Proceedings—AIEE, Special Technical Conference on non-linear Magnetics and Magnetic Amplifiers, Philadelphia Conference, Oct. 26-28, 1960. A specialized variation of the MAD-R technique described by Dr. Bennion, has been developed for applications wherein the advance drive pulses for two or more core devices must be asynchronous. An example of this circuit is shown in U.S. patent application, Ser. No. 50,695, now abandoned, filed Aug. 19, 1960, by John C. Mallinson, a continuation of which issued as U.S. Patent No. 3,178,694. While application experience has uncovered more and more uses for the transfer loop-core coupling described in the Mallinson application, it has at the same time indicated certain operational deficiencies with respect to total range of operation of the unit in the presence of expected temperature and drive supply variation.

More particularly, the specialized variation above mentioned includes a feature wherein the coupling loop which operates to transfer intelligence from core to core, links the outer leg of a minor aperture of one core and the inner leg of the same relative minor aperture of a succeeding core. This feature may be termed Leg 4 to Leg 3 transfer referencing the outer and inner legs of each minor aperture. While certain embodiments of the specialized variation, as for example devices made in accordance with the above mentioned Mallinson application, have proven satisfactory in operation, such devices fall far below, in total limits of operation, standard MAD-R circuits, having transfer loops coupling a succeeding core major path or a receiving minor aperture of such core. In a word, the specialized variations under consideration are being used, but, because of limited range of operation are recognized as the weak link in MAD-R systems.

Accordingly, it is an object of the present invention to provide a MAD-R device having transfer loops coupling the outer leg of the transmitting aperture of one core to the inner leg of the transmitting aperture of a succeeding core in conjunction with an improved circuit extending the range of operation of the device.

It is a further object of the invention to provide a MAD-R device having a Leg 4 to Leg 3 transfer loop with circuit and drive improvements extending the range of operation of the device to be compatible with other MAD-R circuits.

It is another object of invention to provide an improved MAD-R device and method for controlling the characteristics of the operational range thereof.

Other objects and attainments of the present invention will become apparent to those skilled in the art upon a reading of the following detailed description when taken in conjunction with the drawings in which there is shown and described illustrative embodiments of the invention; it is to be understood, however, that these embodiments are not intended to be exhaustive nor limiting of the invention, but are given for purpose of illustration in order that others skilled in the art may fully understand the in-

2

vention and the principles thereof and the manner of applying it in practical use so that they may modify it in various forms, each as may be best suited to the conditions of a particular use.

The foregoing objects are attained in the present invention through the addition of windings which operate to provide magnetomotive forces sufficient and properly phased to prevent backward transfer from a given transmitting core to a receiving core during the transmission phase of the given core. The circuit of the invention incorporates such windings without additional supply requirements by having the added turns supplied by existing advance circuits. Additionally the invention contemplates use of different drive turns ratios with different types of prime drive current to achieve desired control over the operational range characteristics of the circuit of the invention.

In the drawings:

FIGURE 1 is a schematic diagram of a portion of a series of magnetic cores with the circuit of the invention incorporated in a shift register circuit;

FIGURE 1a is a schedule of the function and identity of winding turns N for the circuit of FIGURE 1;

FIGURE 2 is a range map for the device of FIGURE 1; FIGURE 3 is a range map showing the operation of prior art devices; and

FIGURES 4 and 5 depict range maps showing the relationship of winding turns ratios to range of operation.

Referring first to FIGURE 3, there is shown a range map representative of the range of operation of prior art devices, as for example, the shift register device shown in the above mentioned patent to Mallinson. With respect to MAD-R devices, this type of range map has come to be accepted as the basic and standard gauge of unit operation with the shape and spread of the curve shown therein being determinative of success or failure. The abscissa and ordinate of FIGURE 3 represent values of prime and advance currents I_A and I_P , in milliamperes and amperes, respectively. The area defined by the curve in FIGURE 3 corresponds to a region of bistable operation, i.e., where ones and zeros are sustained faithfully in a closed-loop shift register.

Consider, for example, that a given MAD-R unit is supplied with I_A and I_P values to operate at point OP_1 , as shown in FIGURE 3. At this point, and at any point within the curve shown, binary intelligence in the form of one or zero will be retained or transferred between cores in the unit without alteration. As one of the hard facts of commercial use of magnetics, components of the driver circuits supplying I_A or I_P change their operating parameters in the presence of time, heat and the like. Additionally, voltage supplies to the I_A and I_P driver circuits vary substantially, resulting in variations in I_A and I_P from a given initial point of operation to points such as OP_2 , OP_3 and OP_4 . This is particularly true wherein I_P is supplied by a D.C. source or by a pulse source phased to overlap, in time, the I_A pulses. Finally, the magnetic unit itself will exhibit changes in operation determined by the temperature coefficients of the magnetic material and the copper wire employed in the unit. These changes manifest themselves by shifting the ambient curve T_A of FIGURE 3, downwardly and to the left with increases in temperature and upwardly and to the right with decreases in temperature, as indicated by curve positions T_{+A} and T_{-A} , respectively. There is also a change in range size, usually to a smaller area at T_{+A} and a larger area at T_{-A} .

Consider, for example, increases in I_A and in I_P caused solely by supply voltage variations which, in combination, result in the device operating point becoming OP_2 . A device experiencing elevated temperatures and operating with range T_{+A} will operate improperly, spuriously losing intelligence. Consider the same case with no change in I_P .

and a substantial increase in I_A to produce an operating point OP_3 in conjunction with an increase in temperature shifting the range to T_{+A} . This would also cause spurious operation of the magnetic unit. Similarly, a decrease in temperature to the range position T_{-A} combined with slight changes in I_A and I_P will result in an operation point OP_4 and malfunction of the unit. In digital devices as distinguished from analog devices, all expected variations and operational tolerances must be arranged so as to preclude the loss of even a single bit of intelligence.

If a given MAD-R device has a range as depicted in FIGURE 3, compensation or expensive extra steps must be taken when the device is to be utilized in conjunction with other MAD-R units or other electronic units which must meet military and civilian specifications. For example, special high cost voltage supplies and high cost driver circuits must be employed to limit variations of the operating point outside of the curve of the range of operation. Additionally, in critical applications, special environment controls and isolation procedures must be employed to prevent the magnetic core material and copper conductors from being exposed to changes in temperature resulting in transposed ranges of operation. The meaning of this is that MAD-R circuits having ranges as shown in FIGURE 3, are basically incompatible with other MAD-R units with respect to total range of operation.

Referring now to FIGURES 1 and 2, there is shown the improved circuit of the invention and its range of operation for certain drive turns ratios and prime current applied. The range map shown in FIGURE 2 is substantially identical to the design range map of standard MAD-R units. As indicated in FIGURE 2, variations in I_A and I_P and variations in temperature may be quite substantial without resulting in any of the operating points OP_1 - OP_4 being outside of the overlap between the positions of the range maps for ambient, elevated and reduced temperatures.

In FIGURE 1, three multi-aperture cores **10** are shown and represent the O_1 , E_1 , O_2 cores of a unilateral shift register employing Leg 4 to Leg 3 transfer loops.

Each of the cores **10** is comprised of a hard-fired ferrite magnetic material having a substantially square hysteresis loop exhibiting a defined bistability to accommodate the storage of distinct intelligence states in binary form. The particular geometry shown to represent cores **10** in FIGURE 1, is that of a standard four minor aperture core manufactured by the Indiana General Corporation of Valparaiso, Ind., and identified as their material No. 5209. The core is generally symmetrical and includes a central major aperture **12**, with four symmetrically disposed minor apertures **14** of substantially the same diameter. The core is eared adjacent the exterior of each aperture such that the cross-sectional area, through any section of the core, is substantially the same with the cross-sectional area being substantially equal in each half of the section through a minor aperture. In each core **10** the legs denominated L_3 and L_4 represent receiving and transmitting core legs, respectively.

While single core structures are shown, it is fully contemplated that the invention may be adapted to composite core structures defined by a single slab of ferrite or even other magnetic material exhibiting similar characteristics and including individual bit positions which simulate individual cores.

The circuit shown in FIGURE 1, is driven in the usual MAD-R cycle as explained in the article by Dr. Bennion, to advance intelligence from "O" to "E" to "O" cores responsive to the application of Advance O, Prime E, Advance E, Prime O, phases in sequence. The various leads shown forming the advance, prime and transfer leads are Formvar insulated solid copper conductors connected in the polarities indicated in FIGURE 1. The particular turns N shown and identified in FIGURE 1a are related to the currents employed such that a particular NI (or Ni) is sufficient to perform the function required. As will be

demonstrated hereinafter, the ratios of various turns N as well as the characteristics of I_P may be varied to obtain control over the unit range.

Considering now the operation of the circuit in FIGURE 1 with respect to operational sequence, with all of the cores **10** in the zero state conventionally represented by a closed flux path circulating in the clockwise sense (the cores being in negative saturation), the application of a one input to core O_1 via coupling winding **24** and turns N_r will reverse the orientation of flux in the inner leg surrounding aperture **12**, such that the core is then set (the core being half in a state of half negative, half positive saturation). The one input may be considered as a current pulse developed from any suitable source or from a core preceding O_1 . The intelligence states of the three cores **10** will then be one-zero-zero and the normal transfer cycle will result in a prime current I_P being applied to lead **22** to effect a localized reversal of flux in legs L_3 and L_4 of O_1 , the MMF's $N_p I_P$ and $N_b I_P$ acting together to assure that L_4 is fully positively saturated and that the demagnetized state of the core major path is not disturbed. Cores E_1 and O_2 will not of course, be disturbed since the amplitude of I_P is held less than the threshold of a core in the soft or set state and therefore considerably less than the threshold of a core in the clear state. The application of I_A via lead **18** will then operate through turns N_c and N_x to drive core O_1 into the clear state producing a $d\phi/dt$ resulting in a current i_t in loop **26** coupling L_4 . As with standard MAD-R, N_{rf} will set core E_1 ; the content of the cores **10** then being zero-one-zero. The application of I_P to winding **22** will then prime core E_1 in the manner above described and the application of I_A on lead **20** will clear core E_1 and transfer the one to core O_2 to provide an information content of zero-zero-one. Further application of I_P and I_A will advance the information in register to a content of zero-zero-zero. The operation thus far described is similar to that of prior art devices and might be expected to provide a range map as shown in FIGURE 3. The circuit and method of the present invention, which prevents such is in part, based upon discoveries related to the use "hold" turns N_h added to the transmitting aperture of a core and to the characteristics of prime current applied. Before developing this fully, the role of N_h with respect to operational sequence should be in mind.

As a basic point relating to the addition of hold turns N_h to the circuit is the concomitant incorporation of N_h into the advance circuits such that the ADV. O lead **18** includes N_h turns linking core E_1 and the ADV. E lead **20** includes N_h turns linking cores O_1 and O_2 . This feature assures that the MMF, $N_h I_A$ will be properly phased with respect to its purpose in holding a preceding core against being set by back currents developed in a succeeding set core being cleared by I_A . Additionally, since I_A in amplitude and rise time, is partly responsible for the back-current problem, the use of I_A to provide holding MMF is more than merely convenient.

Referring back to the zero-one-zero state of information in register above described, the application of I_P followed by I_A on lead **20** operates to clear core E_1 through turns N_c and N_x to develop i_t in winding **28** and set O_2 as above described. The application of I_A on lead **20** also provides an MMF, $N_h I_A$ operating on the L_4 legs of core O_1 and O_2 simultaneously in a sense to hold the legs L_4 in the clear or clockwise sense. With regard to core O_2 , the holding of L_4 will not prevent the core from being set since it is the inner path including L_3 which is switched to the counter-clockwise state to define a one input. With respect to core O_1 the application of $N_h I_A$ in holding L_4 serves to prevent flux from being switched by the back current i_b flowing in transfer loop **26** and developed by flux switched in L_3 of E_1 . It is to be noted that the sense of i_b is such as to tend to set flux in core O_1 and while the quantity of flux which would be set will be substantially less than necessary for a complete one set,

it can operate to disturb the full clear state. This has been found to have an adverse effect upon the zero level transfer produced when core O_1 is cleared. Thus, for example, if only 20 percent of the core material were set by i_b , the discrimination between one and zero transfer would be reduced from six to one down to two to one; the combination of elastic flux and flux set by i_b operating to so boost the zero flux switched. If this additional quantity of flux is generated in each transfer, a false one will be generated within a single advance cycle. Thus, without N_h , in the sequence above given the intelligence content would be an erroneous one-zero-one following the application of ADV. E rather than zero-zero-one.

In view of the prior art treatment of the explanation of L_3 - L_4 transfer, it might be expected that i_b would be so insubstantial as to have no effect. See for example, the flux arrow diagram in the aforementioned Mallinson case, wherein during advance time leg L_3 appears to be unaffected remaining with the clockwise flux orientation existent before and after the application of ADV. E. In fact, because of this reasoning the relatively poor range map achieved by the prior art, L_4 and L_3 MAD-R transfer was not fully understood. Actual measurements of i_b however, led to the conclusion that with either N_c or N_x and N_h clearing, a very substantial i_b is developed in the coupling loop linking a preceding nontransmitting core to a transmitting core; i_b being higher with $N_c I_A$ clearing than with $N_x I_A$ and $N_h I_A$ clearing. One reason was found to be due to excess material in L_3 adjacent the transmitting minor aperture. Other test evidence led to the conclusion that the i_b developed was due to the MMF caused by i_f in steering flux into the leg L_3 , which has the effect of switching elastic flux if L_3 is properly cleared and both elastic and elastic flux if L_3 is improperly primed in the clear sense. This led to a realization of the role of N_x in increasing flux gain; since $N_x I_A$ not only decreases $d\phi/dt$ in L_3 but also increases $d\phi/dt$ in L_4 to produce a higher i_f . The net effect of $N_x I_A$ is to raise the top boundary when $N_h=0$ by decreasing i_b and lower the bottom boundary by increasing i_f . Extreme values of I_A may cause zero build up.

Viewing now FIGURES 4 and 5, the role of N_h with respect to other turns N_c and N_x and with respect to the characteristics of prime drive will be reviewed. In both figures the range map wherein N_h is not zero, represent the circuit of the invention shown in FIGURE 1. In both figures the range map wherein N_h equals zero, represents the range map of the prior device shown for comparison.

Turning first to FIGURE 4, the D.C. prime case, the circuit of FIGURE 1 may be considered as supplied by a source of D.C. current which is on continuously during the various advance-prime phases. It will be appreciated that the use of D.C. prime considerably simplifies the drive requirements for the circuits since no separate pulse developing means need be utilized and there is no synchronizing problem. For this reason, the use of D.C. prime is attractive in applications wherein cost is more important than total range of operation. Even so, there are certain minimum range requirements. The range map indicated in FIGURE 4 for $N_h=0$ is below these minimum requirements in that there is virtually no range in the area of higher values of I_A and I_p . By making $N_h=3$ in conjunction with $N_c=3$ and $N_x=3$, we see a very substantial improvement in the total area of proper operation with the right-hand boundary being opened up and extended vertically, the top boundary being extended and the bottom boundary being somewhat higher. While the loss of some of the range for lower values of I_A is undesirable, it can be tolerated in certain applications when the remainder of the range is sufficiently large to permit substantial deviations of I_A and particularly when the range permits substantial deviations I_p as it does in the $N_h=N_x=N_c=3$ cases. The reason for the reduction in the bottom boundary with $N_h=0$ is due to higher gain

with respect to forward transfer, wherein the MMF developed by i_f is not opposed by $N_h I_A$.

Turning now to FIGURE 5, I_p is, as indicated, non-overlapping prime. This means that I_p is developed by current pulses, which begin in time after the application of I_A . The range maps shown were made with I_p with a duration of 80 microseconds. As indicated, by making $N_h=3$, $N_c=3$ and $N_x=3$, a very substantial improvement in the range is achieved whereby both the right and left boundaries are opened up and the top boundary is considerably extended. The lower boundary is very slightly reduced, but the area of the range of proper operation is more than doubled with considerable linearity of boundary to provide good overlap in the presence of temperature changes as explained with respect to FIGURE 2. The addition of more N_c turns such that $N_c=6$ with $N_x=3$ and $N_h=3$, further extends the top boundary with a slight depreciation in lower boundary and a slight improvement in right boundary. The improvement appears to hold even where I_p pulses begin before I_A pulses have ceased.

It has been found that by reducing the time of application of I_p to approximately 40 microseconds the lower boundary in both the above curves with $N_h=3$ there is substantial improvement in the lower boundary. It has been also found that a circuit including $N_c=6$, $N_x=3$ and $N_h=1$, will provide adequate operation with ranges somewhat reduced from those indicated, but nevertheless, far superior to the $N_h=0$ cases in both D.C. prime and non-overlapping prime situations.

It will be appreciated from the foregoing that different numbers of turns to those shown may be employed with similar results. It will also be appreciated that in certain circuit applications it is important to have an $N_c I_A$ substantially greater than in other applications. In such case, the use of the ratio $N_c=6$, $N_x=3$, $N_h=3$ is preferred. In other circuit applications due to wiring economy, it is important to have the turns N_c , N_x and N_h equal. FIGURES 4 and 5 indicate that this is possible.

The circuit of FIGURE 1 shows the use of lumped wiring wherein the advance and prime windings have their multiple turns N particular to each core. It is contemplated that linear wiring circuits may be utilized to achieve further labor savings. The provision of $N_x=N_h$ facilitates this since the same physical winding may be made to link the O and E cores in common to accomplish the N_x and the N_h functions. Further savings may be made by having N_c , N_x and N_h equal and common on the cores of the magnetic device.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

I claim:

1. An improved magnetic core device of the type utilized to transfer intelligence in binary form comprising first, second, and third magnetic cores each having a major and a minor aperture, an advance winding threading said first and third cores in a sense to drive said cores into a clear state of magnetization responsive to an advance pulse applied thereto, an advance winding threading the second of said cores in a sense to drive said second core into a clear state of magnetization responsive to an advance pulse applied thereto, a prime winding threading the minor aperture of each of said cores and adapted to drive each core from a set state of magnetization to a primed set state by reversal of flux orientation in the outer leg adjacent the minor aperture of the core responsive to prime current applied thereto, a coupling loop linking the outer leg adjacent the transmitting aperture of

the first core to the inner leg of the minor aperture of the second core, a coupling loop linking the outer leg adjacent the minor aperture of the second core to the inner leg adjacent the minor aperture of the third core, each coupling loop being adapted to transfer the intelligence state of a preceding core to a succeeding core responsive to the preceding core being driven into a clear state from a primed set state, a hold winding including hold turns linking the outer leg adjacent the minor aperture of the second core and connected to the advance winding linking the first and third cores, a hold winding including hold turns linking the outer leg of the minor apertures of the first and third cores and connected to the advance circuit linking the second core, the hold turns linking the outer legs of said cores in a sense to apply an MMF opposing the MMF caused by backward transfer current developed in coupling loops linking preceding cores responsive to a succeeding core being driven to the clear state from the primed set state to transfer intelligence to a further succeeding core.

2. The device of claim 1, wherein the advance windings include other turns linking the minor apertures of said cores in a sense to clear the outer legs adjacent said minor aperture responsive to advance pulses.

3. The device of claim 1, wherein the prime winding is supplied by a D.C. current.

4. The device of claim 1, wherein the prime winding is supplied by prime pulses partially coincident with advance pulses.

5. The device of claim 1, wherein the prime winding is supplied by pulses non-coincident with advance pulses.

6. In a magnetic core device of the type utilizing a plurality of cores, each having a major aperture and a minor aperture, the circuit improvement comprising means linking said cores with suitable current sources to apply phased distinct magnetomotive forces to drive said cores into distinct stable states of magnetization including clear and prime set states through drive windings including

respectively for said states turns N_c linking core major apertures and N_x linking core minor transmitting apertures, N_p linking core minor apertures and N_h linking core major apertures, further means linking the source of current for N_c and N_x turns with holding turns N_h threading the transmitting minor apertures in the same relative sense as turns N_x , turns N_t linking the outer leg of magnetic material adjacent the minor transmitting aperture of one core to turns N_r linking the inner leg of magnetic material adjacent the minor aperture of a succeeding core such as to drive such core into a set state of magnetization responsive to the one core being driven to the clear state from prime set state, the turns N_h being related to the turns N_c and N_x to produce an MMF of a quantity sufficient to counteract the effects developed in a coupling loop connecting a preceding core to the one core as the one core is driven from the prime set state to the clear state to transfer to the succeeding core without having an effect to disturb the magnetic material about the major aperture of the preceding core.

20 7. The device of claim 6, wherein N_c is approximately twice N_x and N_h is less than N_x .

8. The device of claim 6, wherein N_c is approximately twice N_x and N_h is equal to N_x .

25 9. The device of claim 6, wherein N_c is equal to N_x and N_h is equal to N_c .
